FOREIGN PATENT DOCUMENTS

GB 2470188 11/2010

Primary Examiner — Brandon M Rosati*Assistant Examiner* — Aula Soroush(74) *Attorney, Agent, or Firm* — Neal, Gerber & Eisenberg LLP**CLAIM**

The ornamental design for an inhalant dispenser, as shown and described.

DESCRIPTION

FIG. 1 is a perspective view of an inhalant dispenser.

FIG. 2 is a front view of the inhalant dispenser shown in FIG. 1.

FIG. 3 is a rear view of the inhalant dispenser shown in FIG. 1, opposite the front view shown in FIG. 2.

FIG. 4 is a side view of the inhalant dispenser shown in FIG. 1.

FIG. 5 is a side view of the inhalant dispenser shown in FIG. 1, opposite of the side shown in FIG. 4.

FIG. 6 is a top view of the inhalant dispenser shown in FIG. 1; and,

FIG. 7 is a bottom view of the inhalant dispenser shown in FIG. 1, opposite the top view shown in FIG. 6.

The dash-dash broken lines depict portions of the inhalant dispenser that form no part of the claimed design. The dot-dash broken lines define the bounds of the claimed design and form no part thereof.

1 Claim, 6 Drawing Sheets(56)
